(57) **CLAIM**

The ornamental design for a diaper bag, as shown and described.

DESCRIPTION

FIG. 1 is a front perspective view of the diaper bag;

FIG. 2 is a front elevation view of the invention;

FIG. 3 is a left side view of the invention;

FIG. 4 is a rear elevation view of the invention;

FIG. 5 is a right side view of the invention;

FIG. 6 is a top plan view of the invention; and,

FIG. 7 is a bottom plan view of the invention.

The broken lines illustrate stitching and form part of the claimed design.

The broken line circular features in FIG. 7 illustrate portions of the diaper bag and form no part of the claimed design.

1 Claim, 7 Drawing Sheets*FIG. 1***FIG. 2*****FIG. 3****FIG. 4****FIG. 5****FIG. 6****FIG. 7***
